UNITED STATES PATENT OFFICE

162,660

FISHLINE SINKER

Fred P. Humphrey, Los Angeles, Calif.

Application January 13, 1950, Serial No. 7,198

Term of patent 14 years

(Cl. D31—4)

To all whom it may concern:

Be it known that I, Fred P. Humphrey, a citizen of the United States and resident of the city of Los Angeles, county of Los Angeles, State of California, have invented a new, original, and ornamental Design for a Fish Line Sinker, of which the following is a specification, reference being had to the accompanying drawing, forming a part hereof, in which:

Fig. 1 is a rear end view of a fish line sinker showing my new design;

Fig. 2 is a side view;

Fig. 3 is a front end view; and

Fig. 4 is a perspective view thereof.

I claim:

The ornamental design for a fish line sinker, substantially as shown.

FRED P. HUMPHREY.
